UNITED STATES PATENT OFFICE.

EDWARD H. MOYLE, OF LOS ANGELES, CALIFORNIA.

GRINDING MILL FOR ROCKS, ORES, AND LIKE MATERIAL.

Application filed June 18, 1919. Serial No. 305,123.

To all whom it may concern:

Be it known that I, EDWARD H. MOYLE, a citizen of the United States, residing at Los Angeles, in the county of Los Angeles and State of California, have invented a certain new and useful Improvement in Grinding Mills for Rocks, Ores, and like Material, of which the following is a specification.

This invention relates to grinding mills for reducing hard materials such as ore, lime rock, clinker or the like to a fine mesh product.

Objects of this invention are to provide a device which will operate nearly in balance, requiring about the same amount of power to start the device as to operate; to provide a simple device made of the fewest number of parts to give a result; to provide a device which will readily disassociate a compact mass when starting; to provide a device in which a more direct wearing contact surface of the grinding elements will be on the ore, rock or material to be pulverized; to provide a device for quickly unloading or discharging the product when it is pulverized, and finally to provide a device in which the grinding parts can be readily and quickly renewed.

With these and other objects in view, this invention consists of the features, and arrangement of parts, separately and in combination, described in connection with the accompanying drawings, and then more particularly pointed out in the claims.

In the drawing,

Fig. 1 is a plan view of the grinding mill when assembled.

Fig. 2 is a side elevation of the grinding mill as assembled, and partly shown in section through the centre of drum and discharge tube bearing, and delivery tube, as on the lines A—A of Fig. 1, but, showing the driving gear and mechanical intake scoop in elevation, the mechanical feed box in section, and the pinion drive shaft, pinion and their drive parts removed for clearness in description.

Fig. 3 is a sectional detail through the centre of grinding mill, on lines B—B of Fig. 2, and, on lines E—E of Fig. 1, the drive gear,

pinion and pulley shown in outline, while other parts are removed for clearness in description.

Fig. 4 is a sectional detail through the centre of grinding mill, on lines B—B of Fig. 2, and, on lines E—E of Fig. 1, the drive gear, pinion, pulley and other parts not being shown. Fig. 4 shows a modification of the roll or rotor ring shoe in section, within the mill.

Fig. 5 is a sectional detail through the centre of grinding mill, on lines B—B of Fig. 2, and, on lines E—E of Fig. 1, the drive gear, pinion, pulley and other parts not being shown. This figure also shows a modification of the roll, or rotor ring shoe, as explained, the roll shoe being solid, is not drawn in section.

Fig. 6 is also a sectional detail through the centre of grinding mill, on the lines B—B of Fig. 2, and on lines E—E of Fig. 1, the drive gear, pinion, pulley and other parts not being shown for clearness, this figure also shows a modification of the roll or rotor ring shoe, drawn in section, and showing lifting vanes, projections, flights or extensions arranged on its inner periphery, or inner concave surface, the object being to carry the crushed fines upwardly in the circular movement of the mill and so unload or discharge them into the discharge tube, to be carried out of the mill.

Fig. 7 is a sectional side elevation of the grinding mill, drawn on the lines A—A of Fig. 1, the roll or rotor ring shoe as shown in Fig. 6, being drawn in section. The delivery tube and the discharge tube are shown projecting inwardly of the grinding mill to more quickly feed and unload or discharge the finely crushed product of the mill.

Fig. 8 is a sectional side elevation of the discharge tube shown in Fig. 7, but drawn to a larger scale, in order that my description of the discharge launder may be more clearly understood.

Fig. 9 is a sectional detail through the centre of grinding mill on the lines E—E of Fig. 1, and showing a roll or rotor ring shoe supported by double conical friction rollers which are carried between the roller

face or tread of the roll, or rotor ring shoe and the roll race or tread of the die.

Fig. 10 is a sectional detail in elevation through the centre of grinding mill on the lines A—A of Fig. 1, and also shows the roll or rotor ring shoe, having double conical friction rollers, and also the die for the double conical friction rollers; in this figure is also shown the delivery tube and the discharge tube projecting inwardly of the mill.

Fig. 11 shows another form of roller which may be used.

Fig. 12 is an end view of that roller shown in Fig. 11.

Fig. 13 is shown another form of roller which may be used.

Fig. 14 is an end view of the roller shown in Fig. 13.

Fig. 15 is a sectional detail through the centre of grinding mill on the lines E—E of Fig. 1, but showing a roll or rotor ring shoe supported by balls which are carried in the ball tread of die.

Fig. 16 is a sectional detail in elevation through the centre of grinding mill on the lines A—A of Fig. 1, it shows the roll or rotor ring shoe having a ball race or tread to suit the balls, and having a plurality of balls, and having a ball race or tread formed on the die by which the balls are carried. This detail also shows the ore feeding means to the balls, roll or rotor ring shoe and die, and also the lifting means consisting of ribs or extension plates, and the discharging means for unloading the product when the ore, rock or material is pulverized, and carried up or elevated for discharging.

Fig. 17 is a side view of the roll or rotor ring shoe shown in Figs. 15 and 16, showing the feed and discharge openings at the side, and the ribs or extension plates and pockets, for the delivery of the product which is finely pulverized, to the discharge tube.

In some of the different types of grinding mills now in use the working or grinding parts are very greatly out of balance, requiring a large excess amount of power to start the mill, over the amount of power required, when it has attained its proper speed when in operation. So that a comparatively large engine is required in this case, which necessarily is more expensive in cost of installation and up-keep.

In starting up that type of grinding mill which is greatly out of balance, the torque strain is very great on its gudgeons and bearings, causing considerable breakage. The gearing and belts, gudgeons and shafts, must necessarily be made of a larger and of a greater driving surface, in order that they will be durable and strong enough to start the mill in operation.

In the starting up of some of the other grinding mills of a more uneven balance an

electric motor is required having a very strong torque or pulling power said to amount to as much as 240 per cent excess torque action, and the motor is designed as such with the object in view of preventing the burning out of the armature when starting up the mill. It will be seen that with an unaxial roll shoe being nearly in balance with the cylinder of the mill, that this condition is avoided, and so allowing of a motor of any well known standard design.

The grinding parts such as balls and the like which are within that type of grinding mill that is greatly out of balance and when once in operation on the grinding of ores, rock or material, and when grinding wet, are exceedingly hard to start again after the load or charge of the ore is once set, by reason of stoppage of the mill, so that the balls or like grinding parts with the intermixed material, when the mill is started up again, causes an excessive torque action, and which at times causes a considerable breakage to that type of mill, it also requires excess power, and an over plus bearing surface which is necessary for the driving of the mill.

In that type of over-balanced grinding mill using a multiplicity of balls of various sizes mostly all located in the mill and below the center line of axis, the wear is naturally towards excess, by reason of the greater comparative weight of the ball, over that of the ore, rock or material, as a certain point of the convex surface of each of the balls, is always opposing or contacting with each other and so wearing itself with the opposing ball, without effective efficiency on the ore, and thereby giving an unnecessary maximum of wear and loss of metal, when in the crushing and pulverizing of the ore or other material.

Other types of mills are very cumbersome and heavy by reason of their design which require a necessary slow speed, and making it difficult to transport into many places, while the cost of up-keep of those types of mills is necessarily high, by reason of the excessive wear of balls and screens.

My invention relates to a comparatively high speed grinding mill, in which a roll or rotor ring shoe or series of rolls or rotor ring shoes is used within a grinding mill, said roll or rotor ring shoe having no fixed or established mechanical axis, being driven firstly by the surface of the die within the grinding mill, which is in contact with the outer surface of the roll or rotor ring shoe, and thereafter, in conjunction with the ore or rock or material, as it is fed into the interior of the mill, or, in other words, by the surface of the die within the mill, through the ore, rock or other material, to the surface of the roll or rotor ring shoe, or a series of rolls or rotor ring shoes.

My invention also relates to that type of mill which is nearly always in balance, as it will be seen, that the centre or axis of the roll or rotor ring shoe is nearly on, or in relation to, the operating centre of drum, by which the die is carried, so that, this eliminates the unnecessary torque which causes the breakage, as is so common in other mills, when starting, and then in operation.

It will also be seen that the roll or rotor ring shoe when it is slightly in movement, and when starting or operating the mill, will act as an agitator or stirrer, and will at once relieve the charge of ore or rock from its quiescent and compact state, and put it into a live and disassociable state, particularly so when the mill is pulverizing wet.

It will also be seen that, in the feeding and pulverizing of ores of my type of mill, whether pulverizing wet or dry, that I obtain a maximum wearing or crushing surface on the ore, rock or material, by reason of the inner surface of the die being in natural and direct contact with the ore, rock or material, when the surface of the roll or rotor ring shoe is in movement or in rotation with the mill.

In my invention I have also shown a means by which the pulverized product can be raised or elevated, when in suspension within the mill, and by its own mechanical crushing means, when the mill is in operation and grinding the ore, rock or other material. The ore being ground by the exterior surface of the roll or rotor ring shoe, and then the crushed or pulverized product which is held in suspension within the roll or rotor ring shoe, is elevated or carried up by the vanes, pockets or the like, which are located in or on the interior surface of the roll, or rotor ring shoe, and this product so raised, is then unloaded or deposited, on, or into the helical discharge screw or tube of mill, so that it can be quickly carried out of the mill, and so conveyed to any type of screens, hydraulic classifiers, tanks or the like, for any after treatment which may be necessary.

I have also shown by this invention, a means whereby friction rolls or balls may be used between the roll or rotor ring shoe and the ring die, and thereby causing a lesser friction in the operation of the grinding mill on ores, rock or material, as well as giving a greatly increased capacity.

The present invention consists of a cylinder or drum, formed by heads 1 and 2 and shell 3 and 4, fastened by bolts *a*, *b* and *c*.

To the shell 3 and 4 is fastened a ring die 5, of a good wearing material, and preferably made in sections, and fastened by the bolts 6. The side liners 7 also made of a good wearing material are preferably made in sections, being fastened to heads 1 and 2 by bolts 8.

On the tubular extensions 9 and 10 of heads 1 and 2, respectively, bearings 9^a and 10^a are turned to suit bearing blocks 11 and 12, respectively, these bearing blocks may be of the ball and socket type as shown at 70 13, or of any other adaptable type, and may have an extended base plate 11^a and 12^a as shown. On the tubular extension 10, is fastened a circular discharge lip 14, by bolts 15. A discharge tube 16 having in its interior 75 a circular projection or flight 17, formed to act as a conveyor and used to quickly convey and discharge or unload the pulverized ore, rock or other material from the mill after pulverization. It is removably fastened to tubular extension 10 of head 2 by a circular flange 18^a erected around the exterior of discharge tube 16 and having holes therein so that it may engage with bolts 15, and so be rigidly held in place at the end and 80 between tubular extension 10 and discharge lip 14 by said bolts 15.

The projection or flight 17 which constitutes the conveyor can be made of a direction suitable to the operating direction of the 90 mill. As the mill shown in Fig. 3 is arranged to operate against the hands of a watch, the projections or flights 17 could be arranged left-hand in order that the pulverized product would be discharged outwardly of the mill.

On the tubular extension 9 of head 1 is arranged and fastened a driving gear 18 of a suitable design for driving the mill; instead of this gear 18, a pulley or other device 100 (not shown), could be used to take the place of this gear 18, when it should be necessary or more feasible to drive direct, as the mill being nearly in balance, could be so operated under certain conditions, thereby dispensing with the gear pinion 19 and its drive mechanism, consisting of shaft 19^a, pulleys 19^b with bearing blocks 19^c, pulleys 19^b are of the tight and loose pattern when this driving gear is so used.

The bearing blocks 11 and 12 are fastened to base plates 11^a and 12^a by bolts 11^b and 12^b, while the bearing blocks 19^c of shaft 19^a are preferably fastened to the same base plates by bolts 19^a. The base plates 11^a and 12^a are preferably fastened to concrete as I have shown by the foundation bolts 11^c and 12^c, but this type of grinding mill could also be fastened to timber, as the strain or torque lines are greatly eliminated.

A mechanical scoop or spiral feeder 20 made with one, two, or three intake openings is fastened to the tubular extension 9 of head 1 by bolts 21 and in practically the same manner as discharge lip is fastened to the tubular extension 10.

A delivery tube 22 having in its interior a circular projection or flight 23 formed as a conveyor, and used to quickly convey the ore, rock or material to the interior of the 130

mill, to be pulverized; this delivery tube 22 is also removably fastened to and between the tubular extension 9 on head 1 and mechanical scoop or spiral feeder 20, by bolts 21, in the same manner as the discharge tube 16 is fastened. A suitable delivery box 24 is placed for the receiving of the coarse ore rock or material to be pulverized, and so formed that the mechanical scoop or spiral feeder 20 can be easily and quickly loaded with the ore rock or material, to be delivered to the delivery tube 22 having the proper conveyor flights 23 therein of a proper hand or helix, so that the crushed ore rock or material may be quickly delivered to the interior of the grinding mill for necessary pulverization.

Within the drum or cylinder of the grinding mill comprising the heads 1 and 2, shell 3 and 4, and ring die 5, and their companion parts, is placed a roll or rotor ring shoe 25, which is unaxial, or, in other words, without a stationary axis, this roll or rotor ring shoe 25 having a circumference or periphery 26 of a less surface than the circumference or internal peripheral surface 27, which is the inner wearing surface of the ring die 5. To place this roll or rotor ring shoe 25, bolts *a*, *b* and *c* are removed, and a proper tackle or lifting means is applied, by engaging with lifting eye 28 on shell 3, and to which is fastened the sectional parts of the ring die 5 by bolts 6 or any other well known means of fastening or interlocking the joint of ring die 5 when made in sections, and which is preferably parted in conjunction with the joint line 29 of shell 3 and 4.

As the external or outside diameter 26 of roll or rotor ring shoe 25 is less than the internal diameter 27 of ring die 5, it will be seen that the centres are unlike or opposed to each other as shown at 30 and 31, that shown at 30 being the centre of the surface of ring die 5 and the drum or cylinder, while that shown at 31 being the unaxial centre of the roll or rotor ring shoe 25.

In general practice these centres 30 and 31 may be arranged comparatively closer or nearer to each other than that shown, should it be necessary.

Feed openings 32 are formed from the inner surface of this roll or rotor ring shoe 25 to the outer surface 26 as shown in Fig. 3, these openings are made to suit the condition of operation and the direction of travel of the roll or rotor ring shoe 25 within the mill. I have shown one type of opening in Fig. 3, this feed opening 32 which is used to distribute the ore, rock or material to the contact or pulverizing surface between roll or rotor ring shoe 25, and die surface 27, is shown with a longitudinal or elongated opening in the length of the roll or rotor ring shoe, and having a

hopper like inlet 32^a for part of the depth 65 of the opening, and then an expanded or enlarged opening to the outer peripheral face 26, the curvature of the feed openings 32 are shown as the most suitable and efficient when roll or rotor ring shoe 25 and mill is revolving or operating against the hands of a watch as shown by the arrow 33.

This roll or rotor ring shoe 25 could be reversed if necessary by removing same from the mill, reversing side for side and 75 then replacing, and then the mill could be run in the opposite direction or with the hands of a watch, with the same efficiency. The alternate feed openings 34 are shown opposed or in opposition or staggered to 80 the feed openings 32 in order that the ore rock or material may be more evenly distributed through this roll or rotor ring shoe 25 to the die to be pulverized.

It will be seen that this roll or rotor ring 85 shoe 25 when in operation within the mill when crushing ore rock or material will be unaxial or without stationary axis, or in other words will constantly change its axis depending on the charge of ore, the 90 feeding of the ore through the openings 32 and the hardness of said ore rock or material.

The centre of gravities of grinding mill 95 with the ring die 5 and of the roll or rotor ring shoe 25 will be so near equal, that the power necessary to start this type of mill, will be very nearly the same as when in operation, it being seen, that while there is a considerable weight in roll or rotor ring 100 shoe 25, that nearly one-half of that weight is practically on top, or on the opposite side of the centre line 30 of mill.

It will also be seen, that, with a slight circular movement of the mill, that the ore 105 rock or material which is within, if wet, will immediately become agitated thereby, so that the torque action is limited or at a minimum, this generally being the cause of breakage when starting up and operating 110 the other mills.

I have shown the feed openings 32 and 34 in roll or rotor ring shoe 25, Figs. 2 and 3, as for a certain type of ore, these openings however could be made of various shapes, 115 elongations and directions as diametrical, conical or grizzly like or diagonal to insure easy discharge, or these openings could be, as shown in Fig. 4, Fig. 6 and Fig. 7.

The roll or rotor ring shoe 25 could be 120 free from opening if found necessary, when operating on certain types of ore rock and material, as I have shown at 25^a of Fig. 5, (the ring not being drawn in section) by so decreasing its width in its relation to the distance between the side liners 7 of the mill shown in Figures 2 and 3, and thereby allowing the ore rock or material

to be fed along the sides of this roll or rotor ring shoe as at 25^a, or, the roll or rotor ring shoe 25 could be made very nearly the same width, as between side liners 7, as shown in Figures 2 and 3, by having feed openings 36 located around the outer face of roll or rotor ring shoe 25, so that, in this case, with the roll or rotor ring shoe 25 shown plain as in 25^a of Fig. 5 or as described, with the feed openings 36 shown in Fig. 2, a charge of spherical balls or any other shape material such as scrap metal, or short pieces of shafting or any other material, or, flint pebbles could be used in conjunction with the roll or rotor ring shoe 25, or 25^a in the mill, by so feeding them into that inner area and upon surface 37, when the shell 3 is removed, or, they could be fed in the ordinary manner through the mechanical scoop or spiral feeder 20 and to the delivery tube 22 and in the same manner in which the ore, rock or material is fed, so that, both the inner periphery and outer periphery of the practically balanced roll or rotor ring shoe 25 could be utilized, for the pulverizing of the ore rock or other material which is fed to the mill.

In Figs. 2, 3, 4, 5, 6, and 7, I have shown a single roll or rotor ring shoe, but I do not wish to confine myself to a single roll or rotor ring shoe, as a plurality or multiplicity of these rolls could be used side by side if necessary and in the same manner as I have described.

As the inner circumference 27 of the wearing surface of the ring die 5 is greater than the outer wearing circumference 26 of the roll or rotor ring shoe 25 it will also be seen that both wearing surfaces will change their position at every revolution of the mill. In fact, these surfaces, by reason of being concave and convex will constantly rub with each other on the ore, rock or other material, and so tend to speed its pulverization thereby giving a subsequent large capacity.

As the mill in its operation will be nearly in balance it will be also seen that its number of revolutions or its speed can be considerably greater, than in that of an unbalanced mill.

In Fig. 4 I have shown a roll or rotor ring shoe 25 as having circular grinding shoes 38 connected by side walls 39, the face 40 of this shoe acting as a flight or shelf or bucket, for carrying up the finely pulverized product and discharging same upon and into the discharge tube 16 which is fitted with an internal projection of a design suitable, one of the designs of which I have shown at 41 of Fig. 7 and Fig. 8. The finely pulverized product when discharged upon this internal projection 41, of the discharge tube 16, will fall in the diametrically and helically slotted way 42, and be so deposited upon the

inner surface of this helical screw conveyor 65 so adapted to act as a discharge launder as at 43, and the pulverized product so carried quickly into that part of discharge tube 16, at its point of connection which is better shown at 44 of Fig. 7.

The tube 16^a being auxiliary to the discharge tube 16 is used as a carrier for the T shaped internal launder or helical screw conveyor as shown at 41 and 43 with helical opening or slotted way as at 42, and with a 70 turned up flange as shown at 43^a which acts as a retainer when conveying the pulverized product to discharge tube 16. The tube 16^a could also be perforated if found necessary in order that the pulverized product would 75 be more quickly delivered to discharge tube 16 as it would also fulfil the office of carrier of the pulverized product to the discharge tube 16.

In the placing of the roll or rotor ring shoe 25, or, when placing its renewal, and when the delivery tube 22 and discharge tube 16 project inwardly as shown in Figs. 7, 8, and 10, it will be necessary that the circular discharge lip 14 is first removed, and 80 then the discharge tube 16 is drawn outwardly and sufficiently, for the removal of the old roll or rotor ring shoe 25 and the placing of a renewal or new roll or rotor ring shoe 25.

The delivery tube 22 could also project inwardly and within the roll or rotor ring shoe 25 if it should be found necessary, and so also be removed, when found necessary, by removing mechanical scoop or spiral feeder 100 20 from the tubular extension 9, and in the same manner as the discharge tube 16 is withdrawn.

In Fig. 6 I have shown the roll or rotor ring shoe 25 connected in the same manner as shown and described in that of Fig. 4, but, on the inner surface I have shown lifting vanes, projections, flights or extensions 45 having an angle 46 and 47 to constitute a bucket groove or receptacle, for the delivery of the finely crushed product up and above the tubular opening 48 within which the discharge tube 16, and delivery tube 22, is placed, so that, these buckets, grooves or receptacles will carry up the finely pulverized material, and dump or discharge same at a proper position or angle upon the inner projecting end of discharge tube 16 to be so carried outwardly of the mill as I have previously described. These buckets, grooves or receptacles can be made of various shapes and designs, to accomplish the purpose heretofore explained, others of which I have shown in Figs. 9, 10, 15 and 16. I, however, do not limit myself to these shapes or designs, as other practical shapes could also be used to suit the condition, and to give the same result.

The roll or rotor ring shoe 25 shown in Fig. 7 is drawn in section on the line D—D of Fig. 6 and showing the feed openings differently disposed in their relation to each other, as shown by dotted lines 49 and 50, said numbers 49 and 50 to correspond with the same numbers as I have shown, in Fig. 6.

In the Figs. 2, 3, 4, 5, 6 and 7, I have shown a roll or rotor ring shoe 25 of various designs, but they are all bearing upon this same principle of crushing ores, rock or like materials, between the concave surface of the ring die 5, and the convex surface of the roll or rotor ring shoe 25 or 25^a, and I am aware, and do assert that this principle can be embodied into a still more frictionless device, and thereby giving a still greater amount of wearing surface, by which the ore rock or material may be pulverized, and, so increasing its efficiency, capacity and utility in a given space, and, this I have shown by several modifications as in Figs. 9, 10, 15, 16 and 17, and, also with various kinds of rollers which may be used as shown in Figs. 11, 12, 13 and 14.

In the Figs. 9 and 10, I illustrate and show the roll or rotor ring shoe as at 25^b, and the die 5^b, of the mill with a plurality of double conical rollers 51 arranged there-between, and which, and in conjunction with the roll or rotor ring shoe 25^b and die 5^b, as shown in Figs. 9 and 10, comprises the mechanism by which the ore, rock or material is pulverized with less friction. I have shown the unaxial centre 31, or, without a stationary axis, of the roll or rotor ring shoe 25^b as before mentioned in these figures, as somewhat magnified, in order that it may be more clearly understood, but, this centre may be placed as near as practicable to the centre of mill 30 and die 5^b, as it should be found necessary, for the reason that, as the internal wear takes place, that the two centres will increase in their distance from each other.

In Fig. 10 I have also shown the delivery tube 22, by which the ore rock or material is fed to the mill, as projecting inwardly for a certain distance of the mill, and the discharge tube 16 as likewise shown, this may be modified however to suit certain conditions.

In Fig. 11 is shown a roller 52 having smaller diametrical extensions 53 by which a plurality of these rollers could be connected to side walls similar to that shown at 39 of Fig. 4. Plate 39 then having bearing eyes or holes to accommodate diametrical extensions 53.

Fig. 12 is an end view of roller shown in Fig. 11.

Fig. 13 is another form of roller which could be used in place of double conical roller 51 as I have shown in Figs. 9 and 10, the roll or rotor ring shoe, and the die,

would then have straight wearing or contact faces as shown in Fig. 5.

Fig. 14 is an end view of roller shown in Fig. 13.

In Figs. 15, 16 I have shown the roll or 70 rotor ring 25^c and the die 5^c of the mill arranged with a plurality of balls 54. I have shown the die 5^c made in four sections, this could be made, however, in more or less sections if necessary. 75

As shown in Figs. 15, 16 and 17, the ore rock or material is carried into the mill in the ordinary manner, through and by means of the delivery tube 22, and it then passes into the interior of roll or rotor ring shoe 80 25^c, and from there through feed and discharge openings 55, at each side of roll, and then down an inclined clearance passage 56, to and between the plurality of balls 54, and the ball face or tread 57 of the roll or rotor ring shoe 25^c, and the ball race or tread 58 of the die 5^c, to be pulverized.

The ribs or extension plates 59 with pockets 60 within the roll or rotor ring shoe 25^c, are, as I have previously explained, for 90 the carrying and delivery of the finely pulverized product, up and to the discharge tube 16 which may be located as shown, or projecting inwardly of the mill, as I have also shown in Figs 7, 8 and 10. 95

The double conical rollers 51, and the balls 54, or any rollers or like friction and pulverizing devices, some of which I have shown or described could be placed within the mill and in the same manner as the roll 100 or rotor ring shoe 25, 25^a, 25^b or 25^c are placed, or, a special feed hole, with its cover and appurtenances, could be arranged on either heads 1 and 2 or shell 3 and 4.

Ore rock or material is fed in the same 105 manner to the roll or rotor ring shoe 25^b of Figs. 9 and 10 by and through the delivery tube 22 and then through feed openings 55^a or side openings 55^b to be pulverized between the double conical roller 51 110 and the roller face or tread 61 of the roll or rotor ring shoe 25^b and the roll race or tread 62 of the roll die 5^b.

It is to be understood that the construction which I have illustrated and disclosed herein is illustrative merely and that it is not restrictive; and that the invention may be embodied in other forms; for example, the roll or rotor ring shoe, being unaxial, can be changed into various shapes 120 in order that the ore rock or material may be pulverized and elevated for a quick discharge, and with a die suitable. The discharge tube could also have many other and various changes in form and construction, while the die could also be arranged in plurality when a plurality of rolls or rotor ring shoes are used, all without departing from the spirit of this invention. 125

Having thus described my invention 130

what I claim as new and desire to secure by Letters Patent is:

1. In a pulverizing mill having an operating cylinder with hollow bearing means, 5 the combination of a flat surface rotor ring shoe having curved feed and discharge openings therein formed from the inner surface of rotor ring shoe to the outer flat surface of rotor ring shoe, a ring die 10 surface of a greater diameter than the outer flat surface of rotor ring shoe, the ring die removably fastened to cylinder of mill bearing, means for supporting and operating the cylinder of the mill, means for feeding the rock ores or like material through the bearing means for supporting operating cylinder to the feed openings in rotor ring shoe, and means for discharging 15 the pulverized product from the mill through the other bearing means for supporting the operating cylinder.

2. In a pulverizing mill, the combination of a rotor ring shoe, with a plain pulverizing face, a ring die surrounding the rotor ring shoe having a corresponding plain pulverizing face, the diameter of the pulverizing face of the ring die being of a greater diameter than the pulverizing face of the 20 rotor ring shoe, means for feeding the rock, ore or like material between the pulverizing faces of rotor ring shoe and the ring die, means for discharging the product from between the pulverizing faces of rotor ring 25 shoe and the ring die, the ring die fastened to the cylinder of mill, and means for operating the cylinder of mill.

3. In a grinding mill, the combination of an unaxial rotor ring shoe having curved 30 feeding and discharging openings therein by which the rock ore or material is delivered to or discharged from the pulverizing face of the rotor ring shoe, a ring die having an inner wearing face to correspond with the pulverizing face of the rotor ring shoe but of a greater diameter, means for fastening the ring die to the cylinder of mill, and means for operating mill cylinder.

4. In a grinding mill, the combination 35 of a cylinder, a die fastened therein having a plain pulverizing face, an unaxial rotor ring shoe with a corresponding plain pulverizing face through its periphery and provided with curved passages for feeding the ore rock or material from the inner 40 face of rotor ring shoe to the outer pulverizing face of the rotor ring shoe, means for returning the pulverized rock ore or material from the outer pulverizing face 45 of rotor ring shoe to the inner face of rotor ring shoe, means for discharging the pulverized rock ore or material from the cylinder, means for supporting the cylinder, and means for operating the cylinder, die and 50 rotor ring shoe.

5. In a grinding mill, the combination of a cylinder having a ring die therein, tubular trunnions on said cylinder, a freely rotating ring shoe having a plain contact surface engaging with said die, and having 55 openings through its periphery, means for feeding material into said cylinder through one of said trunnions and means extending into said cylinder and in the other trunnion for discharging the pulverized material 60 from the cylinder.

6. In a grinding mill, a cylinder formed sectional, and having exteriorly formed removing and lifting means, heads with tubular extensions formed for bearings and 65 fastened to cylinder, means within the tubular extensions for delivering and discharging the ore rock or material to be pulverized, directly to or from any designated point of the interior of the cylinder, 70 bearing blocks adapted for bearings, a die fastened axially to and within the cylinder, and adapted to engage and drive an unaxial roll or rotor ring shoe, an unaxial 75 roll or rotor ring shoe having curved feeding and discharge passage ways located therein, said roll or rotor ring shoe arranged within the die and to be driven by the die, and means for revolvably operating the cylinder.

7. In a grinding mill having a longitudinal sectionally formed cylinder provided with separating and lifting means, heads fastened to cylinder having tubular bearing extensions, a die fastened to the interior 80 of the cylinder having plain grinding face, an unaxial roll or rotor ring shoe having an exterior plain grinding surface with curved circular feeding means arranged therein by which the ore rock or material can pass from the interior surface of the unaxial roll to the exterior plain outer grinding surface, means within one of the tubular bearing extensions for delivering the ore rock or material directly within the inner surface of the 85 unaxial roll and onto the curved circular feeding means arranged within the unaxial roll so that the ore may be distributed evenly to the exterior plain grinding surface of the unaxial roll, and onto the grinding die, 90 the unaxial roll of a lesser outer diameter than the inner diameter of the plain grinding face of the die, and provided with curved feeding means which are used conjunctively for discharging and elevating the 95 pulverized material so that it may be discharged, means for operating the feeding, grinding, distributing, elevating and discharging means.

8. In combination with a grinding mill 100 rotatable about an axis and provided with intake and discharge openings, said mill being formed of a sectional formed cylinder, a sectional formed grinding die fastened within the cylinder having a plain contact or 105

- grinding face, an unaxial roll or rotor ring shoe having a plain exterior grinding face to contact the internal or grinding face of the grinding die, curved means for feeding the ore rock or material to be pulverized to and between the grinding face of die and unaxial roll or rotor ring shoe, conveying and unloading means projecting through the discharge opening and longitudinally within the interior of grinding mill, and means for operating the mill rotatably around and with the axis, for feeding pulverizing and discharging the pulverized ore rock or material.
15. 9. In combination with a grinding mill rotatable about an axis and provided with intake and discharge openings, having a sectionally formed cylinder and a sectionally formed grinding die fastened to and within the cylinder, an unaxial roll or rotor ring shoe to coact with the grinding face of grinding die, means for feeding the ore rock or material to the grinding face of said ring shoe, means for discharging the ore rock or material from the grinding face of said ring shoe, and means for operating the mill rotatably around and with the axis.
10. In a grinding mill rotatable around an axis, the combination of a cylinder having spiral feed intake and spiral product discharge openings, means for lifting the upper section of cylinder for the taking out and the replacing of renewal parts, a die removably fastened within the cylinder, a roll or rotor ring shoe having curved feed openings and elevator lifting means placed within the cylinder to coact with the face of the die, curved feeding means for delivering the material to be pulverized to and between the grinding face of the roll and the grinding face of the die, elevating means for delivering the pulverized product to the spiral discharge opening, and means for operating the grinding mill rotatably around the axis.
15. 11. In a grinding mill, the combination of a cylinder and a die removably fastened to the cylinder, a plain faced unaxial roll within the cylinder having curved feeding and discharging means for feeding the rock or material through the roll and to the die, curved and elevating means for discharging the pulverized product from the plain face of the unaxial roll and the grinding face of the die, means for discharging the pulverized product from the cylinder, and means for operating the cylinder.
12. In a grinding mill, the combination of a revolving cylinder having a plain faced grinding die therein, the plain faced contact surface of said grinding die in driving contact to a plain faced unaxial roll, a plain faced unaxial roll having the horizontal center of said unaxial roll disposed so that the periphery of the said unaxial roll passes around and above the horizontal center of the revolving cylinder and to engage in driving contact with the plain faced surface of the grinding die and having curved means for feeding and discharging the material to and between the contact surface of the unaxial roll and the contact surface of the die, means for feeding the material to be pulverized, discharge tube means for collecting and discharging the material when pulverized, and means for revolving the cylinder of mill.
- In testimony whereof I affix my signature in the presence of two witnesses.
- EDWARD H. MOYLE.
- Witnesses:
- A. B. BREWSTER,
N. L. PERRY.
